CIGAR AND CIGARETTE HOLDER

Sandford P. P. Clarke, Bronx, N. Y.

Application June 16, 1948, Serial No. 33,312

2 Claims. (Cl. 131—175)

1

This invention relates to an improved holder for use by cigar or cigarette smokers, so that the cigar may be largely enclosed and all ashes trapped against falling upon the floor covering, or upon tables and desks.

One of the objects of the invention is to provide a cigar holder with a mouthpiece which is inserted into the mouth of the smoker and within said mouthpiece there is a clip in which the forward end or tip of the cigar is inserted, and which is slidable in the mouthpiece body to permit the insertion of a fresh cigar and the ejection of a smoked cigar stub.

A still further object of the invention is to provide a safety enclosing case for a cigar, which will prevent burning parts of the cigar from dropping on inflammable material, having a mouthpiece at the forward end thereof and a clip slidable in the safety enclosing case and provided with a cap for closing the outer end of the enclosing case.

A further object of the invention is to provide a device of this character with a coiled smoke tube at the forward end of the mouthpiece through which the smoke is drawn from the burning cigar enclosed by the protective case.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of the holder constructed in accordance with the present invention.

Fig. 2 is a side elevational view similar to Fig. 1, but showing the slide in an extended open position.

Fig. 3 is a longitudinal sectional view, showing the slide in closed position with dotted lines added to show the extended or open position of the slide.

Fig. 4 is a transverse sectional view, taken on line 4—4 of Fig. 1, looking in the direction of the arrows.

Fig. 5 is a rear end of the device, showing the perforated cover or cap.

Fig. 6 is a longitudinal sectional view of a modified form of the invention.

The holder, according to the first form of the invention shown in Figs. 1 to 5, includes a protective case 10 which is large enough to enclose a complete cigar.

2

The forward end of this case 10 is threadedly engaged at 11' with a mouthpiece 11, which is designed for insertion in the mouth of the user, and in this mouthpiece 11 a coiled smoke tube

12 is inserted, so that its forward end is projected with a force fit into the smoke passage of the bite 13 of the mouthpiece 11, and its rear end is disposed slidably into a concentric hole formed in a clip 20 within the case 10. The forward end of the tube 12 is provided with a washer 12' which limits insertion of the end of the tube 12 into the smoke passage of the bite 13 to a position in which the adjacent ends of the tube 12 and the bite 13 are flush as shown in Fig. 3.

15 The case 10 is formed with air holes 14 and a longitudinal slot 15, and the case wall is substantially cylindrical from the mouthpiece 11 to the open rear end thereof. The longitudinal slot 15 does not extend through the rear end of the case, thus leaving a stop 19.

19 The clip 20 is slidably positioned within the case 10 to have the tip or forward portion of the cigar snugly fitted therein. The wall of the clip 20 is connected by a pin 21 to a slide 22 located 25 outwardly of the case 10, the pin 21 slidably extending through the slot 15. This pin is formed with a head 21' thus coupling the inner clip to the sliding member or bar 22 which is formed arcuately in cross section so as to have a matching fit on the outside of the cylindrical case 10.

29 The rear end of the sliding bar 22 is provided with a cap 23 having air holes 24 therein. This cap is adapted to enclose the outer end of the cylindrical case 10, so that no large amounts of cigar ash will drop from the case.

35 By sliding the internal clip 20 toward the outer end of the slotted enclosing case 10, the tip of the cigar may be easily inserted into the clip and then the cigar may be shifted entirely within the case 10 by pushing on the cap 23 or pin head 21'. Before this is done, the cigar should, of course, be ignited in the usual manner.

40 The cigar may be smoked while completely enclosed by the case 10, and as the ash forms on the burning end of the cigar, it is confined by the case 10 and the cap 23 from falling on the floor or on any table or desk.

45 The perforations in the case 10 and cap 23 allow sufficient air to enter the outer or service mouthpiece 11, so that normal combustion and full production of tobacco smoke is obtained.

By pulling the cap 23 outwardly or pushing the pin head 21' forwardly, any ash which has accumulated in the case 10 may be discharged.

55 At no time will any live or burning particles of

the tobacco escape from the case 10. In fact, the entire device, with a burning cigar, may be safely placed in a garment pocket, without danger of the garment catching fire from the burning cigar.

The coiled smoke tube serves to cool the smoke as it is drawn into the mouth of the smoker, and the inner end of this smoke tube is centered with reference to the inner clip 20, so that smoke will freely enter the coiled tube which is surrounded by air. The service mouthpiece has only a single perforation or hole, through which the smoke is discharged to the mouth of the smoker.

Fig. 6 shows a modified construction of the invention, wherein the case 10^a is constructed without the longitudinal slot 15. The clip 20^a is connected by a longitudinal member 22^a to the cap 23^a, which is provided at the outer arm 22^b, which engages the outer face of the case 10^a. Otherwise the construction is the same as that shown in the previously described views and the various parts may be recognized by the similar reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a safety holder for burning cigars and the like having a perforated tubular case closed at one end by a hollow mouthpiece provided at its inside with a coiled cooling tube having one end extended concentrically into the adjacent end of the tubular case with a cap closing the other end of the tubular case and a clip slidably positioned within the tubular case to have the end of the cigar mounted therein, means interconnecting the cap and clip so that when the cap is moved to open the said other end of the tubular case to have a cigar positioned therein the clip will be slid to the said other end of the tubular case to receive the cigar, said interconnecting means comprising an elongated bar extending from the cap along one side of the tubular case, the clip being normally positioned at the end of the tubular case

closed by the mouthpiece and formed with a concentric hole into which the said one end of the cooling tube extends, the tubular case having an elongated longitudinally extended slot in the side along which said bar extends, and a pin extended from the free end of said bar through said slot and connected to the clip.

2. In a safety holder for burning cigars and the like having a perforated tubular case closed at one end by a hollow mouthpiece provided at its inside with a coiled cooling tube having one end extended concentrically into the adjacent end of the tubular case with a cap closing the other end of the tubular case and a clip slidably positioned within the tubular case to have the end of the cigar mounted therein, means interconnecting the cap and clip so that when the cap is moved to open the said other end of the tubular case to have a cigar positioned therein the clip will be slid to the said other end of the tubular case to receive the cigar, said interconnecting means comprising an elongated bar extending from the cap along one side of the tubular case, the clip being normally positioned at the end of the tubular case closed by the mouthpiece and formed with a concentric hole into which the said one end of the cooling tube extends, the tubular case having an elongated longitudinally extended slot in the side along which said bar extends, and a pin extended from the free end of said bar through said slot and connected to the clip, said bar being laterally arched to fit snugly about the tubular case to retain said bar against pivoting about the pin when the cap is removed from the said other end of the tubular case.
